UNITED STATES PATENT OFFICE.

PATRICK J. CULHANE, JR., OF CLEVELAND, OHIO, ASSIGNOR TO THE HYDRAULIC STEEL COMPANY, OF CLEVELAND, OHIO, A CORPORATION OF OHIO.

RIVET HEATER.

Application filed June 2, 1921. Serial No. 474,507.

This invention relates to electrical rivet heating devices of the type in which the rivets are clamped between a pair of electrodes and are heated by passing an electric current 5 through them.

It is the object of this invention to provide a rivet feeding mechanism capable of positioning cold rivets between the clamping electrodes as the heated rivets are with- 10 drawn.

In the drawings forming a part of this specification,

Figure 1 is a vertical section showing the clamping electrodes and operating connec- 15 tions therefor in elevation.

Fig. 2 is a central vertical section through the rivet magazine and feeder.

Fig. 3 is a view showing a vertical section through the magazine and feeder in 20 a plane in right angles to that shown in Fig. 2.

Fig. 4 is a detail view of the cut-off plate forming a part of the reciprocating feeder.

The rivet heating mechanism is mounted 25 upon a carriage 1 and is of an old and well known type in which the rivets are clamped between a stationary upper member 2 and a movable electrode member 3 which engage opposite ends of the rivets and through 30 which the electric current passes. The movable electrode 3 is connected by means of a rod 4 to a treadle lever 5 to which is attached a treadle 6. Interposed between a stationary bracket 7 on the carriage and a collar 8 on the rod 4 is a compression spring 9 which 35 serves to normally maintain the treadle 6 in elevated position and the electrode 3 in clamping position.

Secured to the upper stationary member 40 2 is a vertical conduit 10 forming a magazine for rivets. The member 2 has a passage 11 registering with the interior of the conduit 10 for the passage of rivets and is provided with a transversely extending cham- 45 ber 12 to receive a slidable rivet feeding, and contact or electrode member 13. The sliding member 13 has an aperture 14 in the forward end thereof of sufficient diameter to permit the passage of a rivet when 50 brought into alinement with the conduit 10, and the lower wall of the chamber 12 has an aperture 15 registering with the conduit 10 and passage 11. The sliding member 13

carries a cut-off plate 16 which fits against the upper wall of the chamber 12 and has a keyhole slot 17, the enlarged portion 18 of which is at the rear end thereof and in register with the passage 11 when the member 13 is in forward position as shown in Fig. 2. Extending across the chamber 12 between the slide 13 and plate 16 are a pair of cross bars 19 and 20 which prevent movement of the head of the rivet resting on the slide 13 when it is retracted. The sliding member 13 has a guide pin 21 attached to the rear end thereof. The guide pin 21 slides in a bracket 22 carried by the stationary member 2. Interposed between the bracket 22 and the slide 13 is a compression spring 23 which normally holds the slide 13 in forward position as shown in Fig. 2. Adjustably attached to the lower movable electrode 3 and suitably insulated therefrom is an operating bar 24 having an outwardly projecting beveled portion 25 engaging a correspondingly beveled laterally projecting ledge 26 on the slide 13.

The springs 9 and 23 normally hold the movable electrode 3 in clamping position and the slide 13 in forward position, as 80 shown in Fig. 2. When it is desired to feed a cold rivet to heating position between the electrodes the operator steps on the treadle 6 lowering the electrode 3 against the action of the spring 9. On downward movement 85 of the electrode 3 the beveled portion 25 of the bar 24 engages the beveled ledge 26 on the slide 13 and retracts the slide 13 against the action of the spring 23 until the aperture 14 in the slide 13 registers with the 90 passage 11, whereupon the rivet resting upon the top of the slide 13 drops through the apertures 14 and 15 into engagement with the electrode 3. The movement of the electrode 3 is not sufficient to free the upper 95 end of the rivet from the aperture 15 but is sufficient to clear the upper end of the rivet from the slide 13 so that the slide can move back over the rivet. Rearward movement of the cut-off plate 16 moves the 100 enlarged portion 18 of the slot 17 out of register with the passage 11 and brings the narrow portion of the slot into a position straddling the rivet resting on the slide 13. This allows the rivet on the slide 13 to drop 105 freely when the aperture 14 is brought into

alinement therewith, but presents a barrier against the passage of the head of the superposed rivet.

When the operator releases the treadle 6 the electrode 3 is raised by the spring 9, the slide 13 is released and spring 23 forces the slide 13 to rearward position. Upward movement of the electrode 3 clamps the rivet resting thereon against the under surface of the slide 13 and upon completion of the rearward movement of the slide 13 the enlarged portion 18 of the slot 17 again registers with the passage 11 and permits the column of rivets to drop until the head of the lowermost rivet rests upon the slide 13.

Having described my invention, what I claim is:

1. In a rivet heater, a clamp comprising a pair of opposed electrodes, a rivet magazine, means for operating said clamp and a reciprocating feeder operably connected to said clamp operating means for transferring rivets from said magazine to said clamp.
2. In a rivet heater, upper and lower rivet clamping electrodes, means for moving the lower electrodes toward and from the upper electrode, a rivet magazine carried by said upper electrode, means for moving said lower electrode and rivet feeding means operably connected to said electrode moving means.
3. In a rivet heater, upper and lower rivet clamping members carrying electrical contact members for engaging opposite ends of a rivet, a rivet magazine carried by the upper clamping member, the contact member carried by the upper clamping member being slidably mounted and movable across

the lower end of said magazine to feed rivets from the magazine into position between the clamping members.

4. In a rivet heater, a stationary clamping member, a clamping member beneath the stationary member and movable toward and away therefrom, a vertical tube forming a magazine for rivets mounted upon said stationary member, said stationary clamping member having a passage therethrough in alignment with said tube, a combined feeding and contact member movable across said passageway, a spring for moving said feeding member in one direction, a cam carried by said movable clamping member and engageable with said feeding member for moving said member in opposition to said spring and means for moving said movable clamping member.

5. In a rivet heater, a rivet magazine comprising a vertical conduit, a vertically movable electrode beneath said conduit, a slideable electrode member movable transversely across the lower end of said conduit, cut-off means carried by said slideable electrode member whereby movement of said electrode member permits a single rivet to drop into engagement with the vertically movable electrode member and prevents passage of other rivets permitting said slideable electrode member to return to a position closing said conduit, means for moving said vertically movable electrode member and means for simultaneously moving said slideable electrode member.

In testimony whereof, I hereunto affix my signature.

PATRICK J. CULHANE, JR.
